BALL MILLS

Everett Chapman, West Chester, Pa., assignor to Nordberg Manufacturing Company, Milwaukee, Wis., a corporation of Wisconsin
Continuation of application Ser. No. 537,376, Sept. 29, 1955. This application Dec. 23, 1959, Ser. No. 861,492
28 Claims. (Cl. 241—175)

This is a continuation of Serial No. 537,376, filed September 29, 1955, now abandoned.

This invention resides in the field of grinding and is a new and improved device and several modifications thereof for grinding material in a ball mill or the like.

This invention represents an addition to and an improvement over the invention or inventions, methods and developments shown in application Serial No. 511,665, filed May 27, 1955, which discloses generally a grinding bowl, chamber or track mounted to rotate in two directions at once about two converging axes. The grinding bowl, chamber or track is rotated in one direction about one axis but in the opposite direction about a second axis. The speeds of rotation are such that material undergoing grinding and a charge of grinding elements in the chamber are ranged around the inner surface of the chamber by artificial gravity due to centrifugal force and at the same time the charge and grinding elements are sloshed or oscillated at a pre-selected frequency to create a violent grinding action within the enclosed mass of material and elements.

With the general disclosure of that application as a background, one of the primary objects of my invention is an improved form of what I shall term a generally upright gyratory grinding device in which the grinding chamber is rotated about one axis by a power means separate from a second power means which rotates the chamber about a second axis but constructed so that the first power means operates at constant speed.

Another object is a grinding chamber and table structure generally of the above type in which the chamber or grinding bowl has a depending hollow shaft which serves both as a support and as a discharge for ground material.

Another object is a new and improved structure for controlling the operation of such a grinding bowl.

Another object is a grinding bowl of the above type with its associated structure in which the bowl will be stationary, relative to the base, when only the table is being rotated.

Another object is a grinding device of the above type with means for quickly and easily varying the grinding angle between the two axes.

Another object is a grinding device of the above type characterized by a new and improved form of discharge for ground material.

Another object is a grinding device of the above type in which artificial gravity, due to centrifugal force, is set up in the bowl by a constant speed power source and slosh or oscillation of the material undergoing grinding is effected by a separate variable speed power source.

Other objects will appear from time to time in the ensuing specification and drawings in which:

FIGURE 1 is a side view of one form of my device;

FIGURE 2 is an enlarged view similar to FIGURE 1, but with the details of the base and bowl omitted and showing the driving connections, in section;

FIGURE 3 is a partial section of the bowl used with my device;

FIGURE 4 is a section of an alternate bowl form;

FIGURE 5 is an intermediate supporting platform or stool, in section, with a number of alternatives;

2

FIGURE 6 is a diagrammatic showing of a control circuit and drive for the device in FIGURES 1 and 2;

FIGURE 7 is a section similar to FIGURE 2 of a modified form;

5 FIGURE 8 is another variant shown in section; and FIGURE 9 is still another variant.

In all of the forms illustrated, the bowl is indicated by the letter "B," the base by the letter "F," and the table by the letter "T."

10 In FIGURES 1 and 2, the table T has a platform 10 supported by a suitable bearing 12 on the base through a depending hollow shaft 14 or the like. The table is powered by a suitable electric motor 16, or otherwise, which is geared in a suitable manner to a shaft 18 for driving the table shaft 14 through suitable gearing 20.

15 A gear housing 22 in the base encloses the above gearing with a portion 24 of the table shaft extending through the housing by a suitable bearing 26. This bearing is held in position by a threaded nut 28, or the like, with a seal 30, and the exposed end of the table shaft carries a plurality of slip rings 32 suitably bolted or otherwise held in position.

20 A stool or platform 34, shown in detail in FIGURE 2, is mounted in a longitudinal groove in the upper surface 25 of the table and is composed of a suitable frame-like structure with top plates 36 disposed at an angle to each other and defining a mounting socket.

25 The grinding chamber or bowl B is mounted on a plate 38 which is screwed or otherwise secured to a hollow 30 shaft 40 forming a tubular outlet and support for the bowl. A gear box 42 surrounds the shaft with upper and lower bearings 44 and 46 so that the bowl can rotate freely. A suitable electric motor 48 or the like is mounted on and extends at a suitable angle or is disposed in any 35 suitable position on the gear box and is adapted to drive the bowl through suitable gears 50. A suitable lock ring 51 is threaded to the lower end of the hollow shaft to seal and hold the lower bearing 46. A replaceable wear resistant sleeve 52 is held in the inside of the hollow 40 shaft by a flange 53 which is locked in a groove between the bowl and shaft, and a suitable guard or screw element 54 may extend above it into the chamber to allow passage of ground material but to block the grinding balls. The 45 platform or stool 34 has suitable openings in its sides at 55 and in the bottom at 56, so that appropriate leads can be carried up from the slip rings 32 to the motor 48.

50 It should be noted by this structure that the table T is driven by a power source which is mounted on the base or frame, while the bowl power source takes the form of an electric motor mounted on the table. In this form, the bowl motor can be used as an effective counter-weight and has the additional advantage that a novel control can be effected, to be explained in detail hereinbelow.

55 It should be noted in FIGURE 1 that the table rotates about a generally upright axis X concentric with its shaft 14. The bowl rotates about a second axis Y inclined to the first axis X, concentric with the hollow outlet sleeve 49, and intersecting the first axis at the point Z generally at the geometric center of the grinding chamber or bowl.

60 I have referred to the chamber or grinding track as a bowl, and in using that term in the claims, it should be understood that I do not intend for the term necessarily to cover only a perfect sphere. This is particularly true 65 since I have found that an asymmetric bowl other than a perfect sphere is very desirable under certain circumstances, depending upon the size of the unit involved, the type of material undergoing grinding, the rotative speeds desired, whether grinding wet or dry, and the grinding angle used.

70 The bowl might be made up of a number of sections or halves. For example, I might use three tops and

three bottoms, each set including a long top and bottom, a regular or spherical top and bottom, and a short top and bottom. Each lower half has an axial opening which is adapted to line up with the hollow outlet shaft 40, while each upper half has an axial opening which forms an inlet. The upper half 58 and lower half 59, bolted together at 60, or welded or otherwise secured, may be considered to represent a perfect or near perfect sphere in FIGURE 3. I might elongate or shorten either half or both axially along the vertical axis while retaining the same equatorial diameter. Thus, the slosh action of the balls and material undergoing grinding encounters a changing radius of curvature above and below the equator if either a long or short top or bottom is used. I might use a top and bottom which are both short. Or I might have them both long. In either case, the cross section would be an ellipsoid. On the other hand, I might use a long top with a short bottom, or a short top with a long bottom. Or I might combine either with a regular or hemispherical top and bottom. Thus, by combining all possible tops with all possible bottoms, I provide at least nine possible bowl shapes, any combination being usable with the unit shown in FIGURES 1 and 2. One of the important points behind these bowl shapes is that they are constructed to be easily and equally interchanged on the gear box so that if the grinding conditions change, a new chamber may be substituted to meet the changed grinding conditions.

In FIGURE 4, I have shown a part of a bowl half in which the bowl is formed in three sections 69, 70 and 71, welded or otherwise connected at 72, and the middle section may be a hardened steel wear belt because the grinding is done in this zone. Also the bowl halves in FIGURE 3 could be of different material and/or hardness if most of the grinding was done in one half.

The bowl angle—the angle between the axes X and Y—is also an important factor, and I have found it desirable to construct my unit so that this angle can be easily changed. In FIGURE 5, I have shown one form of platform or stool which slides into the longitudinal slot in the table 10. The upper surface of the platform is divided into two plates 73 and 74 which come together at 75. The plates converge and define an angle between them which serves as a saddle or support for the gear box 42 on the bowl, a corresponding angle being formed on the lower surface of the gear box. The gear box and stool or platform may be connected together by suitable screws or bolts along the outer edges of the engaged plates or by any suitable means. The platforms might be varied, however, by rotating both of them, in unison, about the center point 75. Thus, the bowl angle between the axes X and Y will be changed. For example, if the forward plate 73 is raised, the rear plate 74 would be lowered, or vice versa. But the angle between them would remain the same to smoothly mesh with the bottom of the gear box 42. When the gear box is mounted on a different platform or stool, the axis Y of the bowl will intersect the table axis X at a different point, and the platform or stool can be shifted in one direction or the other to again bring the intersection of the axes to the point Z in the general geometric center of the bowl. The specific structure of the stool or intermediate platform in FIGURE 4 is, of itself, unimportant, except that the use of a plurality of such intermediate stools, each giving a different bowl angle, provides a quick adjustment for the bowl angle and, during operation, a rigid mounting for the bowl, regardless of the angle in use. Depending upon the masses of the elements involved, the table 10 and the edges of the stool or platform could be appropriately graduated so that the operator would merely have to position any selected stool in a previously marked position which would automatically bring the intersecting point Z to the geometric center of the bowl.

As is fully explained in application Serial No. 511,665,

the method of grinding involves rotating the table in one direction and the bowl in the other, each about their respective axes. In my construction, if they are rotated at the same speed but in opposite directions, the bowl surface will have no differential rotation relative to the base or ground, and no grinding will take place. To operate such a unit, the bowl must be rotated at a speed substantially in excess of the table speed, so that the difference between the two speeds will be sufficient to centrifugally range the material undergoing grinding and the grinding elements, preferably balls, about the inner surface of the bowl. The centrifugal force desired is dependent on the diameter of the bowl and from this the effective bowl speed can be determined. The effective bowl speed is the difference between the actual bowl speed and the table speed, and therefore the speed imparted to the bowl by its motor must be equal to the desired effective speed plus the table speed. In short, the differential speed or effective bowl speed equals what I term the artificial gravity set up on the contents of the bowl due to centrifugal force.

I find it highly desirable in grinding to maintain this artificial gravity constant, regardless of the table speed, and in FIGURE 6, I disclose one form of apparatus or control mechanism which can be used as a single lever control which will simultaneously increase or decrease both the bowl speed and table speed while maintaining a constant speed differential. The table, indicated diagrammatically at T, is driven through suitable gearing by its motor 16. The bowl motor is indicated at 48, and I have not shown the details of the bowl or gear box for clarity. Both the bowl and the table motors are provided with 3 phase, A.C. tachometer generators 84 and 86 which are suitably connected to 3 phase motors 88 and 90 by leads 92 and 94. A differential 96 with the usual driver and driven bevel gears 98 and 100 and pinion gears 102 is disposed between the 3 phase bowl and table motors. The bowl 3 phase motor drives the driver gear 98, while the table 3 phase motor 90 is geared to the pinion cage 104. Thus the output shaft 106 from the driven gear 100 reflects the difference between the input speeds of the bowl and table 3 phase motors.

To translate this speed differential into control energy for the bowl motor 48 so it will automatically respond to changes in the table speed, a suitable speed governor 198, possibly of the old and well-known flyball type, may be driven by the shaft 106 through suitable gearing so that the output from the flyball frame adjusts a suitable spring 110 which variably compresses a carbon pile 112. The carbon pile is connected in series in a circuit which includes a suitable source of power 114 and a generator field winding 116 for a generator which supplies current through suitable contacts A—B connected to the armature of the bowl motor at C—D in any suitable manner, not shown. The variable compression of the spring 110 is thus translated into a variable resistance in the carbon pile, in effect a rheostat, so that the voltage supplied by the generator 116 is varied to the bowl motor.

Thus a speed differential can be pre-set, and if the speed of the table motor is increased, which normally would decrease the speed differential, the flyball governor immediately increases the voltage supplied to the bowl motor by the generator 116. Thus the speed differential will remain the same even though both the table and bowl speeds change.

In FIGURE 7, I have shown a variant form of drive in which the bowl motor is mounted on the base, not on the table, either next to or otherwise suitably arranged with respect to the table motor. In any event, a drive shaft 118 extends from the table motor and is suitably geared at 120 to a hollow table shaft or stub 122. A second drive shaft 124 from the bowl motor extends through the hollow stub and is supported at its upper and lower ends by suitable bearings 126 and 128, the lower bear-

ing having a retaining nut 130. A similar retaining nut 132 connects a suitable lower bearing 134 for the table stub which is also provided with an upper bearing 136. A gear housing 138, possibly similar in many respects to the gear housing in FIGURE 2, encloses the gearing to shut out dust and dirt. The table carries a depending skirt 140 which also partially covers the gearing and can incorporate dust seals. The tubular or hollow outlet shaft 142 from the bowl is supported by suitable bearings 143 and 144 on the table and may be provided with a seal at 145. This shaft carries a bevel gear 146 which is driven by a bevel gear 148 on the input shaft 124 through and idler 150 mounted in any suitable manner on the table.

One of the important advantages of this arrangement is that the speed of the table does not have to be subtracted from the bowl speed before the bowl will rotate relative to the base. The gears 146 and 148 are of the same size, have the same pitch and the same number of teeth, and are what I term equal. When the bowl motor is not energized and the table motor is rotating the table, the bowl will float around the driving gear 148 and will maintain its same relative position, due to the idler 150 and the fact that the gears 146 and 148 are the same size. Any input to the driving shaft from the bowl motor will immediately be reflected in positive rotation of the bowl. In short, the bowl does not have to initially overcome the speed of the table before it can produce augmented gravity forces on the balls.

In FIGURE 8, I have shown a further modification, similar to FIGURE 7, in that both the table and bowl motors are mounted on the base. One of the disadvantages of the FIGURE 1-6 form is that the angle between the axes of the bowl and table must be split or divided by the idler axis and the angle is fixed in the bevel gears. To overcome this, I mount a second shaft 152 in the gear housing or box which is connected to the bowl motor input shaft 154 by a constant speed variable angle universal joint 156. It should be noted that this joint is housed in the hollow table shaft 158 and the drive is carried to the bowl by equal gears 160 and 162 through an idler 164. By using a constant speed universal joint, the bowl angle can be changed by use of a different stool. Other than this, the details of the gear box, frame and bowl can be the same or slightly modified to accommodate the universal joint and its associated driving structure. For example, a support or platform 164 may be used in the gear box to support the idler and one end of the shaft 152 through a suitable bearing 166, the other end of the shaft being supported at 168 to the top of the gear box. In this form, I again emphasize that due to the idler gear the speed of the table motor does not have to be first overcome by the bowl motor, and all speed put into the bowl by its driving means will be immediately effective to augment gravity regardless of the table speed. In effect, the bowl speed which produces augmented gravity on the balls is totally independent of the table speed.

In FIGURE 9, I have shown a further modification, similar in many ways to FIGURE 8 in that the universal joint and second shaft are used, but in this form the idler is replaced by a chain drive at 170 which also makes all of the bowl motor speed immediately effective to set up the artificial gravity, regardless of the table speed. When using a chain drive of this nature, the sprockets should have equal diameters, and the same number of teeth. The drive to the bowl shaft could also be a compound idler between spur and bevel gears or any other gearing or drive that produces the above effect.

While I have shown and described the preferred form and several modifications, it should be understood that numerous changes can be made without departing from the invention's fundamental theme. Several of the modifications are interchangeable. For example, the bowl forms or shapes in FIGURES 3 and 4 can be used with any of the drives. The specific constant speed differential

mechanism in FIGURE 6 represents only one form. In the claims I have used the term "bowl" and it should be understood that I intend this term to define a generally spherical bowl or possibly axially elongated or shortened or an asymmetric combination of shapes, such as suggested in FIGURE 3. The word "bowl" does not necessarily mean a perfect sphere. The term "bowl angle" refers to the angle between the bowl axis and the table axis. The term "artificial gravity" refers to the centrifugal force imparted to the material undergoing grinding and the grinding elements in the chamber partially due to the bowl motor. The term "slosh" refers to the oscillation or vibration imparted to the material in the chamber due to rotation of the table. I have used the term "table" to designate a rotatable frame or sub-base upon which the bowl is rotatably mounted.

The use, operation and function of my invention are as follows:

This invention is a specific improvement and an addition to the method and apparatus shown in Serial No. 511,665, and it is my intention to augment that inventive disclosure by one or more inventive features or steps. I have shown a separate drive for the grinding bowl which can be mounted on the table, and under certain circumstances this is very desirable. It should be noted that the drive of the bowl, such as shown in FIGURES 7, 8 and 9, essentially is an epicyclic gear or drive train. It is also an object of my invention to provide a variety of bowl shapes composed of a combination of bowl zones or halves, welded, bolted and/or composite metallurgy, each combination being specifically intended for a particular grinding situation. This is further augmented by a mechanism for quickly and easily varying the bowl angle. I also provide a number of motor drives whereby the rotative speed from the bowl motor is entirely effective to set up artificial gravity in the bowl, regardless of the speed of the table. I also provide an improved form of discharge for the bowl, which substantially eliminates any discharge problems and at the same time serves as a support for the bowl.

It should be noted that by my structure, the bowl motor can be a constant speed A.C. unit for any particular grinding assembly, as the artificial gravity created in the bowl should be constant, for example, from 6 to 9 gravities. The slosh imparted to the material undergoing grinding can be determined by varying the speed of the table motor which, by experiment, is one of the most important variables when encountering different ores. The slosh speed defines the type of ball motion, which can thus be selected over a wide range of different actions. By the various arrangements shown, the bowl motor can operate at a constant speed, so that regardless of the slosh imparted to the material, the artificial gravity applied to the material will be constant.

I claim:

1. In a device for grinding, a base, a table rotatably mounted on the base about a generally upright axis, a grinding bowl rotatably mounted on the table, power means for rotating the table, and a second power means on the table for rotating the bowl independently of the rotation of the table.
2. The structure of claim 1 in which the grinding bowl is mounted on the table about a second axis inclined to the table axis and intersecting it generally at the geometric center of the bowl.
3. In a grinding mill, a base, a table rotatably mounted on the base about a generally upright axis, a grinding chamber rotatably mounted in the table about an axis inclined to the first, power means for driving the table and chamber, the chamber being open at its upper end to receive material to be ground, and a hollow outlet shaft extending from the lower end of the chamber into the table concentric with the inclined axis.
4. The structure of claim 3 in which the hollow outlet

shaft is mounted in the table and functions as the support for the chamber.

5. In a grinding device, a base, a table mounted for rotation on the base about a first axis, a bowl rotatably mounted on the table about a second axis, power means for rotating the table in one direction, a second power means for rotating the bowl in the other direction, and means for automatically maintaining a predetermined speed difference between the table and bowl speeds as the table speed varies.

6. The structure of claim 5 in which the bowl axis intersects the table axis generally at the center of mass of the bowl.

7. The structure of claim 5 in which the second power means for the bowl is mounted on the table.

8. In a grinding device, a base, a table mounted for rotation on the base about a first axis, a bowl mounted for rotation on the table about a second axis, power means for rotating the table in one direction and the bowl in the other direction, and means for automatically maintaining a predetermined speed difference between the table and bowl speeds as the table speed varies.

9. In a ball mill, a base, a table mounted on the base for rotation about a predetermined first axis, a grinding chamber mounted for rotation on the table about an axis inclined to the first axis, power means for rotating the table, a second power means for rotating the chamber, and a driving connection between the second power means and the chamber including a constant speed joint.

10. The structure of claim 9 characterized by and including a second shaft in the table which is disposed generally parallel to the inclined bowl axis, the joint being connected to the second shaft, and a driving connection between the second shaft and the bowl.

11. The structure of claim 10 in which the driving connection between the second shaft and the bowl includes a chain drive.

12. The structure of claim 10 in which the driving connection between the second shaft and the bowl includes a gear drive.

13. The structure of claim 12 in which the gear drive includes equal spur gears for the bowl and second shaft, and an idler between them.

14. In a grinding mechanism, a base, a table mounted for rotation on the base about a generally upright axis, a bowl mounted for rotation on the table about an axis inclined to the table axis, power means and a driving connection between it and the table, a second power means and a driving connection between it and the bowl, and means for maintaining the bowl stationary relative to the base when only the table power means is in operation.

15. The structure of claim 14 in which said last-mentioned means includes a chain drive in the driving connection between the second power means and the bowl.

16. The structure of claim 14 in which a driving shaft extends from the second power means, and including equal gears for the driving shaft and bowl with an idler between them.

17. The structure of claim 16 in which the gears and idler are spur gears.

18. The structure of claim 16 in which the gears and idler are bevel gears.

19. The structure of claim 16 in which the driving shaft includes a constant speed joint.

20. In a ball mill grinding device, a base, a table mounted for rotation on the base about a generally up-

right axis including a removable platform, a grinding bowl mounted for rotation on the table about a second but convergent axis defining a predetermined angle with the first axis, the platform having mounting surfaces to support the bowl at the predetermined angle, driving connections for rotating the table and bowl, and power means for the driving connections.

21. The structure of claim 20 in which the bowl power means is mounted on the table.

10 22. In a device for grinding material, a base, a table mounted for rotation on the base about a predetermined axis, a grinding bowl mounted for rotation on the table about a second axis convergent with the first, variable speed power means for rotating the table, and constant speed power means for rotating the bowl.

15 23. The structure of claim 22 characterized by and including means for holding the bowl stationary relative to the base when only the table power means is in operation.

20 24. In a ball mill, a base, a sub-base mounted for rotation on said base about a predetermined axis, a mill body mounted on said sub-base for rotation about an axis inclined to and convergent with the axis of rotation of the sub-base on the base, said mill body having a ball track circumferentially described about and generally concentric with the intersection of the two axes, and a discharge from said mill body including a generally rectilinear tube concentric with the axis of rotation of the mill body.

25 25. The structure of claim 24 characterized in that the tube passes through the sub-base and discharges at a level beneath the sub-base.

30 26. The structure of claim 24, characterized by and including bearing means for the mill body, surrounding the discharge tube.

35 27. In a ball mill, a base, a sub-base mounted for rotation on said base about a predetermined axis, a mill body mounted on said sub-base for rotation about an axis inclined to and convergent with the axis of rotation of the sub-base on the base, said mill body having a ball track circumferentially described about and generally concentric with the intersection of the two axes, motor means for rotating the sub-base in relation to the base, and separate motor means on the sub-base for rotating the mill body in relation to the sub-base.

40 28. In a grinding mechanism, a base, a table mounted for rotation on the base about a generally upright axis, a bowl mounted for rotation on the table about an axis inclined to the table axis, power means and a driving connection between it and the table, a second power means for the bowl, and a driving connection between the second power means and the bowl including an epicyclic drive train.
